UNITED STATES PATENT OFFICE.

LOUIS BILTON, OF EAST LIVERPOOL, OHIO, ASSIGNOR TO THE OWEN CHINA COMPANY, OF MINERVA, OHIO.

DESIGN FOR A PLATE OR SIMILAR ARTICLE.

Application filed June 19, 1926. Serial No. 18,093. Term of patent 7 years.

To all whom it may concern:

Be it known that I, LOUIS BILTON, a subject of Great Britain, residing at East Liverpool, in the county of Columbiana and State of Ohio, have invented a new, original, and ornamental Design for a Plate or Similar Article, of which the following is a specification, reference being had to the accompanying drawing, forming part thereof.

The figure is a plan view of a plate showing my new design.

I claim:

The ornamental design for a plate or similar article, as shown.

LOUIS BILTON.
